FIG. 2.

FIG. 1.

FIG. 3.

UNITED STATES PATENT OFFICE.

GEORGE ADOLPH STEINER, OF SALT LAKE CITY, UTAH, ASSIGNOR TO AMERICAN LINEN SUPPLY COMPANY, OF SALT LAKE CITY, UTAH, A CORPORATION.

TOWEL-HOLDER.

1,256,274.

Specification of Letters Patent. Patented Feb. 12, 1918.

Application filed September 18, 1916. Serial No. 120,652.

To all whom it may concern:

Be it known that I, GEORGE A. STEINER, a citizen of the United States, resident of Salt Lake City, county of Salt Lake, State 5 of Utah, have invented certain new and useful Improvements in Towel-Holders, of which the following is a specification.

The object of my invention is to provide a towel holder from which a single towel may 10 be easily and quickly removed and withdrawn a sufficient distance from the case to permit its convenient use.

A further object is to provide a holder which will occupy less space than usually 15 required for devices of this kind, the towels being folded or partially rolled instead of lying flat as usual.

A further object is to dispense with all 20 springs, weights and pulleys in an article of this kind, thus making it cheaper, more durable and less troublesome to the user of the towels.

Other objects of the invention will appear 25 from the following detailed description.

The invention consists generally in various 30 constructions and combinations, all as hereinabove described and particularly pointed out in the claims.

In the accompanying drawings forming 35 part of this specification,

Figure 1 is a perspective view of a towel holder embodying my invention,

Fig. 2 is a vertical sectional view of the 40 same,

Fig. 3 is a sectional view showing the supporting rod for the towels in the holder.

In the drawing, 2 represents a suitable 45 casing or cabinet, having a base 2' for the reception of the soiled towels. This base

may be used or not, as preferred, the upper 50 or cabinet part of the holder being separable from the base and held in place thereon by clip devices 2''. The cabinet has side walls 3 provided with forwardly and downwardly

inclined slots or guides 4. A rod 5 is mounted 55 to slide freely in said slots and normally rest by gravity in the lower ends thereof.

The forward portion of the cabinet has a shelf 6 extending inwardly beneath the 60 lower ends of the slots and at the forward end of this shelf is a ledge or flange 7. The shelf and a portion of the wall 7' of the cabinet are hinged at 7'' to allow the shelf or ledge 7 and the wall 7' to drop down and 65 expose the interior of the cabinet and permit

the convenient insertion of a bundle of towels therein. A latch device 8 is preferably provided for holding the hinged shelf and its connections in their normal closed position. The forward edge of the shelf is preferably 60 recessed at 8' to receive the flexible connection that is inserted through the towels to allow the convenient removal of a towel from the bundle.

The towels, which I indicate by reference 65 numeral 9, are preferably provided in the corners with gromets 10 and a chain 11 is threaded through these gromets at the laundry, one end of the chain having a ring 11' thereon that is too large to pass through 70 the gromets. When a sufficient number of towels have been strung on the chain, a lock 12 is placed thereon so that they cannot be removed without tearing out the gromet.

In using the device, it is intended to 75 string the towels on a chain or other suitable stringer at the laundry and bring them to the holder ready strung, or the towels may be sent from the laundry unstrung and used loose in the holder. In placing the towels 80 in the casing, the door 7 is unlatched and the part of the front above the hinges is tilted downwardly and the clean towels then thrown over the rod. The front is then closed up and latched, thus gripping the 85 towels between the front door and the rod. The edges of the front end of the towels then rest on the shelf, while the other ends of the towels hang in rear of the rod. If a chain or other suitable stringer is used to fasten the 90 towels together, the loose, free end of the stringer may be connected to the cabinet by suitable means, such as a spring hook or locking device.

One object of stringing the towels together on a chain at the laundry is to prevent pilfering by janitors, or others around an office building or hotel, before the towels are put in the holder, for obviously, if they are strung together through the metal gromets or holes, it will be difficult for any of them to be removed from the bundle without detection. Generally a hundred towels, that being a convenient number to handle in the holder, are strung on the chain or 100 flexible stringer and the end of the chain placed in or attached to the holder, sufficient slack being provided at one end of the chain to allow the towels to be drawn off the pile, one at a time, and conveniently used. 110

The person wishing to use a towel will pull off the upper one of the pile, then pull it down on the stringer, and the depending portion of the stringer will allow the towel 5 to be held out some little distance from the casing and thereby eliminate the objection to many towel holders, where the person is obliged to insert the head into or close to the wall of the casing in order that the towel 10 may be used on the face. Considerable space is economized by folding the towels over the rod and the weight of the towels on the rod will tend to slide it forward, pressing the clean towels against the hinged ledge 15 and down upon the shelf. This forward pressure will hold the clean towels in the front of the case, making them easily accessible to the user and preventing binding of the chain or stringer on the shelf or other 20 parts of the cabinet.

One corner of the towel and chain will be adjacent the recesses 8' in the shelf and as the towels are fed forward automatically through the weight of the bundle, the outer 25 towel will overhang the recess where it can be conveniently grasped and pulled out of the holder by the user.

As the towels are used, they will drop 30 down into the soiled towel receptacle beneath the cabinet, where they will be partially concealed and lying on the floor, will not exert a downward pull on the stringer sufficient to prematurely withdraw the clean towels from the cabinet. I have shown the slack end of 35 the stringer lying in the bottom of the soiled towel receptacle, but it may be attached thereto, if preferred. This, however, would seem such an obvious modification that I have not thought it necessary to illustrate 40 any attaching means herein.

The other end of the stringer having the padlock thereon will normally depend in the rear of the shelf in the cabinet, the weight of the padlock holding the stringer in place 45 allowing the towels to be removed from the bundle and drawn forward to a position for use. It will be noted that the slots 4 extend to a point near the ledge at the front of the cabinet and as the towels are removed from 50 the bundle the rod, actuated by the pressure of those supported by it, will slide forward in the guides, automatically adjusting itself to the reduction in the size and weight of the bundle, and when the bundle is nearly exhausted, the supporting rod will be near the 55 lower ends of the guides bearing with sufficient pressure on the few remaining towels to hold them in place.

A towel of fairly good size can be used in 60 the holder without requiring a cabinet which would be cumbersome and bulky in a toilet room, as the towels are folded in a bundle over the supporting rod instead of lying flat on a shelf, as usual in devices of this kind. 65 Furthermore, no followers or springs are

necessary in a cabinet of this kind, the weight of the towels being utilized for holding the bundle in place.

I claim as my invention:

1. A towel holder comprising a support 70 over which the bundle of towels is folded, a casing for said support having forwardly inclined guides therein wherein said support is slidable by gravity, the rear fold of the towels hanging loosely within said casing, 75 said casing having means for contacting with the forward fold and resisting the forward movement of the towels to allow the outer one to be withdrawn from the bundle without disturbing the remainder. 80

2. A towel holder comprising a casing having guides therein, a towel support mounted to move in said guides and over which support a bundle of towels strung together on a flexible connection is folded, 85 the rear fold of the towels depending within said casing and the forward fold thereof contacting with said casing and resisting movement of said support in said guides but allowing it to slide forwardly under the 90 weight of the towels step by step, as the outer towel is removed.

3. A towel holder comprising a casing having forwardly and downwardly inclined guides therein, a rod mounted to slide in said 95 guides and adapted to support a bundle of towels folded thereover, one fold of the towels depending within said casing and said casing having a shelf upon which the end of the other fold of the bundle is seated, 100 the weight of the bundle sliding the rod forwardly and keeping the towels in contact with said shelf as the towels are removed from the bundle.

4. A towel holder comprising a support 105 having guides therein and a member movable in said guides and on which the folded bundle of towels is placed, said guides being inclined and said member sliding therein under the weight of the towels thereon, said 110 support having means for limiting the movement of said towels and the outer towel being removable from the bundle, the remainder being held on said member through their engagement with said support. 115

5. A towel holder comprising a cabinet having a base for the reception of the soiled towels, a towel support mounted in the upper portion of said cabinet and over which a bundle of towels is hung, said support 120 being mounted to move in guides in said cabinet, said cabinet having a surface against which the bundles of towels are held by gravity, a stringer for the towels having one end depending within said base, 125 the towels being removable one at a time from the bundle and withdrawn from the cabinet on said stringer.

6. A towel holder comprising a cabinet having a hinged front wall section and a 130

shelf carried by said wall section, said cabinet having guides therein and a towel support slidable in said guides and on which the bundle of towels is suspended, one end 5 of the bundle contacting with said shelf and the other depending from said cabinet in the rear of said shelf, a stringer whereon the towels are mounted, the removal of the outer towel of the bundle allowing the re- 10 maining towels to slide forwardly in said guides to automatically feed the bundle to the point of removal from the cabinet, said hinged wall section, when opened, allowing convenient access to said towel support for 15 placing the towels thereon.

7. A towel holder comprising a cabinet having a hinged forward section including a horizontal shelf, an upright ledge thereon extending partially across said cabinet, said 20 cabinet having downwardly and forwardly inclined guides above said shelf, a towel support slidable in said guides and over which a bundle of towels is placed, said hinged section, when opened, permitting the 25 convenient insertion of the towels within the cabinet and upon said support, a stringer

passing through a corner of the bundle of towels, said shelf having a recess to receive said stringer, the removal of the upper towel of the bundle allowing the remainder to 30 slide forward with said support and one end of the bundle of towels contacting with said shelf and the other end depending in said cabinet in the rear of said support.

8. A towel holder comprising a support, 35 a rod mounted for forward movement on said support and over which rod the bundle of towels is hung, said support having a stop for engaging the forward end of the bundle of towels, a stringer for the towels 40 having one end depending beneath said support, the outer towel being removable from the bundle, the remainder being held on said rod through their engagement with 45 said stop.

In witness whereof, I have hereunto set my hand this eighth day of September 1916.

GEORGE ADOLPH STEINER.

Witnesses:

O. A. KNAPP,
Mrs. CHAS. S. KING.
